US0D1057682S

(12) **United States Design Patent** (10) **Patent No.:** **US D1,057,682 S**
(45) **Date of Patent:** **** Jan. 14, 2025**

(54) **COMPONENT FOR A HEADPHONE**

(71) **Applicant:** **Apple Inc.**, Cupertino, CA (US)

(72) **Inventors:** **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Joe Sung-Ho Tan**, Vienna (AT); **Clement Tissandier**, San Francisco, CA (US); **Eugene Antony Whang**, San Francisco, CA (US)

(73) **Assignee:** **Apple Inc.**, Cupertino, CA (US)

(**) **Term:** **15 Years**

(21) **Appl. No.:** **29/932,753**

(22) **Filed:** **Mar. 15, 2024**

(57) **CLAIM**

The ornamental design for a component for a headphone as shown and described.

DESCRIPTION

FIG. 1 is a top front perspective view of a component for a headphone showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the component for a headphone that form no part of the claimed design.

1 Claim, 6 Drawing Sheets

Related U.S. Application Data

a continuation of application No. 29/858,408, filed on Oct. 31, 2022, now Pat. No. Des. 991,217, which is a continuation of application No. 29/840,038, filed on May 25, 2022, now Pat. No. Des. 968,364, which is a continuation of application No. 29/739,074, filed on Jun. 22, 2020, now Pat. No. Des. 953,288.
